UNITED STATES PATENT OFFICE.

CHARLES LE G. FORTESCUE, OF PITTSBURGH, PENNSYLVANIA, ASSIGNOR TO WESTINGHOUSE ELECTRIC & MANUFACTURING COMPANY, A CORPORATION OF PENNSYLVANIA.

CIRCUIT INTERRUPTER.

Application filed November 9, 1918. Serial No. 261,914. Renewed March 11, 1922. Serial No. 543,088.

To all whom it may concern:

Be it known that I, CHARLES LE G. FORTESCUE, a subject of the King of Great Britain, and a resident of Pittsburgh, in the county of Allegheny and State of Pennsylvania, have invented a new and useful Improvement in Circuit Interrupters, of which the following is a specification.

My invention relates to quick-acting circuit interrupters and particularly to actuating electromagnets therefor.

The object of my invention is to provide an electromagnet having two magnetic paths from one of which the flux is adapted to be deflected to the other to obtain quick operation of an armature that shall have a relatively long range of movement.

In co-pending application, Serial No. 258,555, filed October 17, 1918, by C. L. Fortescue and J. B. MacNeill and assigned to the Westinghouse Electric & Mfg. Co. an electromagnet having two magnetic paths is provided with means for deflecting the flux from one path to the other upon a sudden overload in the circuit. In order to cause the flux deflection to occur within a minimum period of time, with this form of electromagnet, the reluctance of the two paths must necessarily be substantially the same. But, in order to obtain a relatively large movement of the armature, it is necessary that the two paths shall be so separated that the reluctance of one of the paths may be relatively large.

In view of the above-specified conditions, I provide an electromagnet having two stationary and two movable pole pieces to constitute two magnetic paths which are normally of substantially equal reluctance. The armature is disposed between the pole pieces and thus, when it is actuated by a spring or other energy-storing device, the movable pole pieces are moved to permit the armature to have a sufficiently great movement. Closed-circuit conductors are provided for damping the movement of the movable pole pieces toward the latter part of their movement.

The single figure of the accompanying drawing is a diagrammatic view of a circuit interrupter embodying my invention.

A direct-current electric circuit 1 is provided with a circuit interrupter 2 that is actuated and controlled by an electromagnetic device 3.

The device 3 comprises a magnetizable core member 4 having two stationary polar projections 5 and 6 and two movable polar projections 7 and 8 that constitute two magnetic paths for the flux in the core member 4. An armature 9 is disposed between the polar projections and is operatively connected, through a rod 10, to the interrupter 2.

A spring 11 normally tends to open the interrupter, and a shunt winding 12, that is connected to the circuit 1, is adapted to so energize the electromagnet 4 as to cause the armature 9 to bridge the polar projections 5 and 6 and thus close the interrupter 2. Windings 13 are disposed on the core member 4 and are so series-connected to the secondary winding of a series transformer 14 that, when the current traversing the direct-current circuit 1 changes quickly, by reason of a short circuit or ground therein, sufficient voltage will be induced in the secondary winding of the transformer 14 to cause current to traverse the windings 13, the latter being so wound, with respect to the winding 12, that the flux which normally traverses the path comprising the polar projections 5 and 6 and the armature 9 will be deflected through the polar projections 7 and 8 to thus attract the armature 9 and permit the spring 11 to quickly open the interrupter 2.

It will be understood that the two paths through the polar projections are normally of substantially the same reluctance, which is essential in order to permit the quick deflection of the flux from one path to the other. However, it is essential that the movement of the armature 9 shall be such as to permit sufficient movement to actuate the interrupter 2.

With the small difference in reluctance between the two paths and the relative closeness of the same to each other, it is not possible to secure sufficient movement of the armature 9. In view of this, the polar projections 7 and 8 are provided with ball bearings 15 that permit the same to be quickly moved, under the action of the spring 11, to such positions as to permit the armature 9 to have the proper amount of movement. Closed-circuit conductors 16 are provided around the portions 17 of the core member 4 for the purpose of co-operating with the portions 18 and 19 of the polar projections 110

7 and 8, respectively, to damp the movement thereof toward the latter part of the armature movement.

From the foregoing, it will be seen that a very small interval of time is required to open the interrupter 2 when a fault occurs on the circuit because the magnetic flux is not opposed but is merely deflected from one path to another of substantially the same reluctance, and that a great movement of the armature is obtained after the flux has been deflected, thereby obtaining quick operation and sufficient mechanical movement to permit effective interruption of the circuit.

15 My invention is not limited to the particular structure illustrated, as it may be variously modified without departing from the spirit and scope of the invention, as set forth in the appended claims.

20 I claim as my invention:

1. The combination with a circuit interrupter, of an electromagnet comprising a magnetizable core member having a plurality of stationary and of movable polar projections constituting two magnetic paths of slightly different reluctance, an armature disposed between the polar projections and connected to the movable member of the interrupter, and a spring for so actuating the armature in one direction as to move the movable polar projections to permit relatively large movement of the armature.

2. An electromagnet comprising a core member having two magnetic paths of different reluctance, an armature for normally completing the path of least reluctance, means for deflecting the magnetic flux through the other path, under predetermined conditions, and means whereby the reluctance of the second path is adapted to be increased only after the flux is deflected.

3. An electromagnet comprising a magnetizable core member, a plurality of stationary and of movable polar projections therefor disposed relatively close together to constitute two magnetic paths, an armature, and means for actuating the armature in one direction and for so moving the movable polar projections as to permit a relatively long movement of the armature.

4. An electromagnet comprising a core member having two stationary polar projections and two movable polar projections constituting two magnetic paths of different reluctance, an armature, a spring for opposing the normal operation of the armature, means for so diverting the magnetic flux through one magnetic path that the spring is permitted to quickly actuate the armature and the movable polar projections, and means for damping the movement of the polar projections.

5. An electromagnetic device for an electric circuit comprising a core member having two stationary polar projections and

two movable polar projections constituting two magnetic paths, an armature, means for energizing the core member to cause the armature to bridge the stationary polar projections, and means for deflecting the flux through the movable polar projections to cause quick movement of the armature, under predetermined conditions.

6. An electromagnetic device for an electric circuit comprising a core member having two stationary polar projections and two movable polar projections constituting two magnetic paths, an armature disposed between the polar projections, means for energizing the core member to cause the armature to bridge the stationary polar projections, means for so deflecting the flux that the armature bridges the movable polar projections, means for assisting the movement of the armature and means for damping the movement of the movable polar projections.

7. An electromagnet comprising a core member having two stationary polar projections and two movable polar projections constituting two magnetic paths, a spring-restrained armature disposed normally in engagement with the stationary polar projections, and means for so diverting the flux from the stationary polar projections that the armature shall be quickly actuated into engagement with the movable polar projections.

8. In an electric circuit, the combination with a circuit interrupter, of an operating electromagnet therefor comprising a core member having two stationary polar projections, two movable polar projections, an armature disposed between the polar projections and operatively connected to the interrupter, a potential winding for so energizing the core member that the armature is normally maintained bridging the stationary polar projections, and a current winding disposed between the stationary and the movable polar projections and energized from the circuit when a quick change in current obtains for so deflecting the flux through the movable polar projections that the armature quickly moves into engagement therewith.

9. In an electric circuit, the combination with a circuit interrupter, of an operating electromagnet therefor comprising a core member having two stationary polar projections, two movable polar projections, an armature disposed between the polar projections and operatively connected to the interrupter, a potential winding for so energizing the core member that the armature is normally maintained bridging the stationary polar projections, a current winding disposed between the stationary and the movable polar projections, for deflecting the flux through the movable polar projections

to quickly move the armature into engagement therewith, and means for retarding the movement of the movable polar projections toward the latter part of their 5 movement.

10. An electromagnetic device for an electric circuit comprising a core member having two stationary and two movable polar projections constituting magnetic paths and 10 a movable armature member, means for so energizing the core member as to maintain the armature in engagement with the stationary polar projections, means for deflecting the flux from the stationary polar 15 projections to the movable polar projections and means for actuating the armature into engagement therewith.

11. An electromagnetic device for an electric circuit comprising a core member having two stationary and two movable polar projections constituting magnetic paths and 20 a movable armature member, means for so energizing the core member as to maintain the armature in engagement with the stationary polar projections, means for deflecting the flux from the stationary polar 25 projections to the movable polar projections, means for moving the armature into engagement therewith and means for damping 30 the movement of the movable polar projections.

12. An electromagnetic device for an electric circuit comprising a core member having two stationary and two movable polar 35 projections constituting magnetic paths and a movable armature member, means for so energizing the core member as to maintain

the armature in engagement with the stationary polar projections, and means for so deflecting the flux from the stationary polar 40 projections to the movable polar projections as to actuate the armature into engagement therewith.

13. An electromagnetic device comprising a core member having two magnetic paths of 45 different reluctance, one path of greater reluctance comprising two movable polar projections, an armature member, a winding for so energizing the core member as to maintain engagement of the armature 50 member with portions of the core member that comprise the path of lesser reluctance, and a winding disposed between the two paths for so deflecting the flux from the path of less reluctance to the path comprising 55 the movable projections as to actuate the armature member into engagement therewith.

14. An electromagnet comprising a core member having two magnetic paths of different reluctance comprising two stationary and two movable polar projections, an armature for normally completing the path of least reluctance comprising the stationary projections, and means for deflecting the 60 flux through the path of the movable projections under predetermined conditions, said projections co-operating to increase the reluctance of that path only after the flux is 65 deflected.

In testimony whereof, I have hereunto 70 subscribed my name this 31st day of Oct. 1918.

CHARLES LE G. FORTESCUE.
